NAIL CLIPPER

John W. Hunt, Pontiac, Mich., and

William A. Hunt, Chicago, Ill.

Application December 2, 1950, Serial No. 198,886

8 Claims. (Cl. 30—28)

1

The present invention relates to manicure equipment, and more particularly to an improved nail clipper and file which is well adapted for being carried in pockets of clothing, ladies' handbags and the like, and which has a cutting mechanism permitting the user to trim the nails of either left or right hand with relatively great ease and facility.

It is an object of the present invention to provide an improved device for trimming fingernails or toenails, which device includes a casing that can be used interchangeably either for enclosing the cutting mechanism when the latter is not in use or as a handle and supporting structure for the cutting mechanism when the latter is to be used for trimming purposes.

It is another object of the present invention to provide a cutting mechanism for a nail clipper, which cutting mechanism includes cutting jaws swivelly mounted so that the jaws can be turned in any desired direction with respect to their supporting structure thereby permitting the user to actuate the jaws when the latter are in the most suitable position to facilitate trimming the nails of either the left or right hand.

It is still another object of the present invention to provide an improved nail clipper as described in the preceding object wherein a lever arm can be used when in one position for actuating the cutting jaws and in another position as a nail file, and further, when the lever arm is in the latter position, it can be selectively used as a file or can be inserted into the casing to be enclosed therein.

It is still another object of the present invention to provide a nail clipper which can be constructed from relatively few and simple parts, thereby permitting production thereof at a relatively low cost, and which is constructed and arranged so that a substantial portion thereof can be fabricated from suitable plastics, lightweight metals or the like, while effecting a rugged but lightweight construction.

Other objects of this invention will appear in the following description and appended claims, reference being had to the accompanying drawings forming a part of this specification wherein like reference characters designate corresponding parts in the several views.

In the drawings:

Fig. 1 is a side elevational view of the nail clipper with the cap screwed to the casing to enclose the cutting jaws therein;

Fig. 2 is a side elevational view of the nail clipper with the cap screwed to the casing in

a reverse position to that of Fig. 1 so that the cutting jaws are outside the casing, and the lever arm for actuating the jaws is shown in its operative position as well as in phantom in its normal position when enclosed in said casing;

Fig. 3 is an enlarged exploded fragmentary view partly in section of the cutting mechanism of the nail clipper shown in Fig. 2;

Fig. 4 is a fragmentary sectional view taken on the line 4—4 of Fig. 2; and

Fig. 5 is a fragmentary view showing a modified form of the cutting mechanism for the nail clippers; and

Fig. 6 is a top view of the modification shown in Fig. 5.

Before explaining the present invention in detail, it is to be understood that the invention is not limited in its application to the details of construction and arrangement of parts illustrated in the accompanying drawings, since the invention is capable of other embodiments and of being practiced or carried out in various ways. Also, it is to be understood that the phraseology or terminology employed herein is for the purpose of description and not of limitation.

Referring to the drawings, Fig. 1 shows an embodiment of the nail clipper in its closed position, in which position it normally will be when carried by the user in his or her pocket or in a ladies' handbag, or the like. As seen in Fig. 1, the nail clipper includes a cylindrical casing 10 having its one end closed and rounded as at 12. The other end 14 is open and is closed by a cap member 16. The latter can be secured to the casing 10 by being screwed thereto, or can be attached in any other suitable manner so that it can be easily removed therefrom. The only requirement of the means for attaching the cap 16 to the casing 10 is that it be constructed and arranged to permit the cap 16 to be secured to the casing 10 in the position shown in Fig. 1, or reversed so as to be secured to the casing 10 in the manner shown in Fig. 2.

The casing and cap construction shown permits all the elements of the cutting mechanism which will be described hereinafter, to be enclosed within the casing so that there will be no sharp edges or ends to snag into the pockets or handbags of the users. This feature of providing a tube-like casing is also advantageous in that such a casing will occupy a relatively small space while providing sufficient room within for housing the various parts of the nail clipper. Also, the cylindrical shape is advantageous in that it permits manufacturing of the casing from

relatively light materials, such as plastics or other metals, and the tubular or cylindrical shape provides a relatively strong construction per unit of weight. If desired, however, the cross section of the casing 10 may be square, rectangular, oval, or the like.

As can be seen in Figs. 2 and 3, a support bracket 18 extends outwardly from one end of the cap member 16. The bracket 18 has a square opening 20 formed therein through which a pin 22 extends whose cross section conforms to the shape of the opening 20. The pin 22 has an enlarged head 24 at its upper end and at its lower end a slot 26 is cut into one side thereof.

A pair of cutting jaws 28 made of spring steel, or the like, and having cutting edges 30 for trimming toenails or fingernails, are provided which are adapted to be swivelly mounted on the pin 22. The cutting jaws 28 have apertures 32 and 34 therein as can best be seen in Figs. 3 and 4. As there shown, these apertures are circular in shape so that the jaws can move axially as well as rotatably on the pin 22.

The upper jaw of the cutting jaws 28 has a depressed portion 36 into which the enlarged head 24 of the pin 22 is received and the lower jaw member has a raised portion 38 for receiving the lug 40 on the support bracket 18. The lug 40 has a serrate surface so as to frictionally resist rotation of the cutting jaws 28. The pin 22 is retained in place on the support bracket 18 by the lever arm 42 which has a rectangular aperture 44 at its one end. The end portion 46 of the lever arm 42 is placed in the slot 26 which extends transversely in the pin 22, and when it is desired to actuate the jaws 28, the lever arm 42 is pivoted about an axis co-extensive with said slot 26 to the position shown in solid lines in Fig. 2. The cutting jaws 28 are closed when the lever arm 42 and the casing 10 are moved together by a pinching action. As is believed understood, the lever arm 42 will then pivot about the fulcrum point 18A on the bracket 18. This causes the pin 22 to be partially lowered through the aperture 20 in the support bracket 18 resulting in the enlarged head 24 of the pin 22 forcing the upper jaw of the cutting jaws 28 downwardly into engagement with the lower jaw. When pressure on the lever arm 42 is released, the jaws will return to their normally open position by virtue of the resilient properties of the spring steel of which they are made.

As is believed readily understood from the above description, the cutting jaws 28 can be turned in any desired position with respect to the support bracket 18 by virtue of the swivel mounting provided. The lever arm 42 and the casing 10 will always retain their relative position with respect to one another by virtue of the mounting construction of the pin 22 and the lever arm 42, since neither the pin 22 or the lever arm 42 can be rotated about the axis of the pin 22.

The lever arm 42 functions not only to actuate the cutting jaws 28, but also can be used as a nail file. The concave surface of the lever arm 42 is cut in the conventional manner to provide a file 42A, and when the lever arm 42 is pivoted to the position shown in phantom in Fig. 2, it can be used for this purpose. The lever arm 42 is suitably curved at 48 to provide the desired curvature for providing the optimum results in filing the nails.

The position of the lever arm 42 shown in phantom in Fig. 2 is the normal position of the

latter when housed within the casing 10, and it is also the normal position when being used to file or clean the nails. The outer tip of the lever arm 42 is pointed in the conventional manner to provide for cleaning fingernails and the like. In order to provide a relatively sturdy nail file for these latter purposes, a wedging device is provided so that the lever arm 42 will be held rather rigidly when in the position shown in phantom in Fig. 2. This wedging action results when the end portion 46 of the lever arm 42 is pivoted into the angular slot provided in the support bracket at 52, Fig. 3. As is believed readily understood, when the lever arm 42 is pivoted to the position shown in phantom in Fig. 2, the outer end portion 46 will be wedged into the angular slot 52 to provide a rigid extension of support bracket 18.

A modified form of the invention is shown in Figs. 5 and 6. This modification of the invention is substantially the same as that shown in Figs. 1-4 with the exception of the cutting jaws 54 which are pivotally connected as at 56, and the coil spring 58 which serves to bias the cutting jaws 54 apart. In all other respects, this nail clipper is the same as that shown in Figs. 1-4.

From the above description, it is believed to be readily clear that the present invention provides a nail clipper which has no sharp edges or snags when it is carried in the closed position shown in Fig. 1. Further, it has swivelly mounted cutting jaws so that the user thereof can turn the jaws to the position which enables him to trim the fingernails or toenails with the greatest ease and facility. Also a rather simple mechanism has been provided for actuating the jaws so that a firm and positive grip can always be had when actuating said jaws, and further, this actuating mechanism can be enclosed within the casing of the nail clipper merely by being pivoted to a position forming an extension of the supporting structure. In addition, this nail clipper can be constructed from relatively few and simple parts permitting production thereof at low cost and it can be made with a majority of the elements being made of plastics or the like.

Having thus described our invention, we claim:

1. In a nail clipper, a support bracket, a pin mounted against rotation on said bracket, cutting jaws mounted on said pin for swivel movement above said bracket, a lever arm pivotally connected to the lower end of said pin and in engagement with a fulcrum point on the lower side of said bracket, said pin extending through the bracket and each of said jaws and having an enlarged head above the upper jaw whereby when said lever arm is pivoted about said fulcrum point the pin will be axially moved with respect to said bracket to open or close said jaws.

2. In a nail clipper as claimed in claim 1, wherein in said cutting jaws comprise a U-shaped spring steel member.

3. In a nail clipper as claimed in claim 1, wherein said cutting jaws comprise a pair of oppositely disposed jaws pivotally connected together and a compression spring is positioned therebetween for biasing said cutting jaws apart.

4. In a nail clipper, the combination of a support bracket having a substantially rectangular aperture therein and a fulcrum point on its lower side, a pin extending upwardly through said aperture and axially slidable therein, said pin being substantially rectangular in cross section to prevent rotation in said aperture, a pair of cutting jaws positioned on the upper side of said bracket

and having round holes therein through which said pin extends whereby the jaws may be swiveled on said bracket, the upper end of said pin having an enlarged head, the lower end of said pin having a transverse slot therein, and a lever arm having its one end extending into said transverse slot and another portion in engagement with said fulcrum point for moving said pin axially on pivotal movement of the lever arm about the fulcrum point so that said jaws will be closed on lowering of said pin with respect to said support bracket.

5. In a nail clipper, the combination as claimed in claim 4 wherein said cutting jaws comprise a U-shaped spring steel member.

6. In a nail clipper, the combination as claimed in claim 4 wherein said cutting jaws comprise a pair of opposite disposed jaws pivotally connected together, and a compression spring is positioned therebetween for biasing said cutting 20 jaws apart.

7. In a manicuring device, the combination of a support bracket having an aperture therein, a pin extending upwardly through said aperture and axially slidable therein, a pair of cutting jaws positioned on the upper side of said bracket and having apertures therein through which said pin extends, the upper end of said pin having an enlarged head, the lower end of said pin having a transverse slot in one side thereof, a fulcrum point on the lower side of said bracket and on the opposite side of said pin from its slot, a lever arm having a transverse pivot member at its one end in pivotal position in said slot for actuating said jaws when said arm is pivoted 25 on the fulcrum and for forming an extension

of said bracket when said arm is pivoted to another position, and an angular slot formed in said bracket for receiving a portion of said transverse pivot member in wedging relation when said arm is pivoted to the other position.

5. A nail clipper comprising a tubular member, a reversible closure member on one end of the tubular member carrying a support bracket, a pin extending through said support bracket, cutting jaws mounted on said pin, a lever arm pivotally connected to one end of said pin and in engagement with a fulcrum point on said bracket, said pin extending through said jaws and having an enlarged portion at its other end so that when 10 said lever arm is pivoted in one direction about said fulcrum point the pin will be moved to open or close said jaws and when the lever is pivoted in an opposite direction to a position forming an extension of the bracket the cutting jaws, lever arm and pin can be housed within the tubular member.
